Patented Feb. 4, 1919.

UNITED STATES PATENT OFFICE.

JOSEPH EDER, OF SAN FRANCISCO, CALIFORNIA.

LEATHER-CUTTING MACHINE.

1,293,059.

Specification of Letters Patent.

Patented Feb. 4, 1919.

Application filed May 6, 1916. Serial No. 95,807.

To all whom it may concern:

Be it known that I, JOSEPH EDER, a citizen of the United States, residing at San Francisco, in the county of San Francisco, State of California, have invented a new and useful Leather-Cutting Machine, of which the following is a specification in such full and clear terms as will enable those skilled in the art to construct and use the same.

This invention relates to leather cutting machines, and particularly to those which are used principally to trim or round the soles of boots and shoes after the soles have been secured in place.

Most sole rounding machines have a great many parts, which not only necessitate more attention and care paid to the machine, but greatly add to their expense. The present invention is strong and rugged, takes up very little room, and has few parts.

The objects of the invention are to produce a machine of low cost which is especially adapted for work in a repair shop, which will trim the soles either before or after sewing, which will also trim heels, which can be used in connection with any kind of a stitcher, round or straight needle, and which will save both time and labor.

For a complete understanding of the invention, reference is made to the accompanying drawing in which—

Figure 1 is a side elevation of the machine;

Fig. 2 is a central vertical sectional view;

Fig. 3 is a top plan view of the machine showing a driving motor connected to it; and

Fig. 4 is a fragmentary perspective view showing the guard and work holder.

The numeral 1 designates the top of a work bench or the like to which the frame 2 of the machine is secured by any suitable means. The frame is preferably cast iron, and is provided with the integral transverse ribs 3 and 4 which run intermediate the top and bottom of the frame and at one side thereof. The rib 3 has a perforated lug 13 extending outwardly from its central portion and a similar lug 3' at one side of its center. These lugs provide bearings for vertically movable elements as will be described.

In vertical alignment with lug 13 but protruding outwardly from the frame itself is a third lug 13', and in alignment with

both lugs, but extending from the frame on both sides is the open-ended bearing 5. This bearing is located at the rib 4. A main shaft 6 turns in bearing 5, and has a cam 7, 60 pulleys 8 and 9 of different sizes, and flywheel 10, all secured to it. The cam 7 is preferably of the uniformly accelerating and retarding type, but other types may be employed.

A rod 12 which carries the knife at its upper end is vertically reciprocated by the cam 7 through an eccentric strap and extension 11, which is pivotally joined at 28 to the lower end of said rod. Lug 13 has 70 an aperture and lug 13' a similar aperture, the two apertures being in vertical alignment and providing bearings for the reciprocating rod 12. The upper end of the latter as indicated by the numeral 30 is split 75 to form a bifurcated portion adapted to clamp removably a knife 14. The knife comprises a flat substantially rectangular steel blade having a concaved or scythe edge 31 near its upper end, and is held so as to 80 form practically a continuation of the reciprocating rod 12.

To the top 22 of the frame an angle iron or angular member 15 is secured as by screws 17, the said member being curved 85 longitudinally as shown in Fig. 1 to fit the frame and is offset therefrom. Its upper angular face thus forms practically a continuation of the curved top face of the frame as Fig. 2 illustrates. A narrow slot 23 is 90 provided in the upper end 22 of the frame to form a guideway for the knife. This slot is closed by the angle iron, the latter thus acting as a guard to keep the knife in its slot.

The lug 3' like lug 13 has an aperture acting as a bearing for a vertically movable rod 18. The end of this rod, which lies below the lug, has a coil spring 21 held on it by any suitable means. The upper end is 100 bifurcated as indicated at 34 and holds removably an arm 19 having a guard portion 20 bent at right angles to the part held by the rod. The guard 20 is itself bent into a U-shaped end located in a substantially 105 horizontal plane, as Fig. 3 shows, and has the depending angular tooth 35 formed out of one side. The action of spring 21 is to lower the rod 18 and hence the guard; thus the tooth 35 normally presses against the 110 angle iron or member 15 on its top face, as illustrated by Fig. 2. This tooth as will be

seen from Fig. 3, is thus used as a work holder and also as a gage when trimming the soles. The U-shaped end of the guard 20 overhangs the upper end of the frame and incloses the knife as the latter moves into its highest position, thus fulfilling its function as a guard; and its peculiar shape also adapts it to be used as a guide by the operator.

10 The rod 18 moves in but one bearing, hence allows a certain amount of lateral play or free motion to the guard 20. This free movement is not however sufficient to allow the guard to contact with the moving 15 knife. When desired, the guard can be raised above the knife by grasping the arm 19 at the first bend.

The machine may be driven through a belt 25 connecting one of its pulleys 8, 9, 20 with a small motor 24. When using the machine the work is held as Fig. 3 shows in dotted lines and is fed by hand with the guard member pressing its tooth 35 against the sole, thereby serving both as a gage and 25 as a work holder. The angle iron or member 15 supports the edge of the sole being trimmed. The rapidly reciprocating knife is so shaped that it cuts quickly and yet smoothly through the leather leaving a 30 smooth edge where it has cut.

The machine itself is quite small, being only ten inches high and eight inches long. Being so small, its construction cost is low and its upkeep almost nothing. The power 35 it consumes also amounts to a very small item. But while small, it saves a tremendous amount of energy by cutting through heavy sole leather. Thus I have found that by its use I can round off thirty pairs of shoes in 40 fifteen minutes or less, all ready for the next operation.

While I have described my invention in considerable detail, I do not wish to be limited strictly thereto, but desire to reserve 45 the right to change and modify my machine in many particulars providing that such changes and modifications come within the scope of the appended claims.

What is claimed is:—

50 1. In a sole rounding machine, a frame having a rigid work rest, a knife vertically reciprocable in said frame at one side of the work rest, means for driving the knife, and a single element forming a combined guard, 55 gage, guide and work holder arranged in front and on opposite sides of the knife and adapted to normally press against said work rest, said element having a limited slidable movement relative to said work rest and 60 frame in the direction of motion of said knife, and a spring for restraining said movement.

65 2. In a manually fed sole rounding machine, a frame, a knife vertically reciprocable in a slot in said frame, means for driv-

ing the knife, and a combined guard, gage, guide and work holder slidably secured to the frame and normally arranged in front and on both sides of the knife and capable of being raised out of surrounding relation 70 to said knife, and comprising an arm having a guard portion bent at right angles in a substantially horizontal plane, said guard portion being bent into a U-shaped portion, one arm of which is formed with a depend- 75 ing angular tooth.

3. In a machine of the class described, an upright frame having a slot in its upper end, a knife reciprocable vertically in said slot, means for driving the knife, an angular 80 member for closing the slot and holding the knife therein while reciprocating, said member also forming a work rest, and a toothed, spring-actuated work holder coöperating with said knife and work rest. 85

4. In a machine of the class described, an upright frame having a curved top face, a knife vertically reciprocable in said frame, means for driving said knife, a rigid work rest secured to the top of the frame adjacent the knife and offset therefrom, said work rest being curved to conform with and form a continuation of the top face of the frame, a spring actuated vertically movable work holder normally pressing against the 90 work rest at one side of the knife, said work holder serving also as a guard for the knife. 95

5. In a machine of the class described, an upright frame, a knife vertically reciprocable in the frame, means for driving the 100 knife, a work rest secured to the top of the frame adjacent said knife and offset therefrom, and a combined work holder and guard movably secured to said frame and including a U-shaped portion having a tooth, 105 said work holder and guard having a spring for normally urging the tooth against said work rest with the U-shaped portion inclosing said knife.

6. In a machine of the class described, an 110 upright frame, a knife vertically reciprocable in said frame, means for driving the knife, a work rest provided at the top of the frame adjacent the knife and offset therefrom, and a work holder normally pressing 115 against said rest, said work holder having a depending tooth, said tooth elevating the main portion of the work holder above the rest and being adapted to serve as a gage.

7. In a machine of the class described, the 120 combination with the upright frame, a drive shaft mounted at the lower end thereof, a cam on said shaft, a rod connected to and receiving motion from said cam, a knife carried by the upper end of said rod, said knife 125 working through a slot provided in the frame, a work rest offset from the frame and knife, and a combined work holder and guard consisting of a spring actuated vertically disposed rod mounted in the frame 130

- at one side of the first-mentioned rod, said spring actuated rod having an arm at its upper end bent inwardly at right angles and again bent into a U-shaped portion inclosing the front and two sides of the knife, said U-shaped portion being provided with a depending angular tooth which engages with the work rest and elevates the said U-shaped portion above said rest.
- 10 8. In a machine of the class described, the combination with an upright frame, a drive shaft mounted at the lower end thereof, a cam on said shaft, a rod connected to and receiving motion from said cam, a knife car-

ried by the upper end of said rod, said knife 15 working through a guide provided in said frame, a rigid work rest offset from the frame and knife, and a combined work holder and guard consisting of a spring actuated vertically disposed rod mounted in 20 the frame at one side of the first mentioned rod and having at its upper end an arm formed with a U-shaped portion inclosing the front and two sides of the knife, and having means to engage the work rest. 25

In testimony whereof I have hereunto set my hand this 27th day of April A. D. 1916.

JOSEPH EDER.
